[57] CLAIM

The ornamental design for a mobile garbage can holder,
as shown and described.

DESCRIPTION

FIG. 1 is a side elevational view of a mobile garbage can
holder showing my new design.

FIG. 2 is a top plan view thereof.

FIG. 3 is a front elevational view thereof.

FIG. 4 is a perspective view thereof.

FIG. 5 is a perspective view of a mobile garbage can
holder showing a second embodiment of my new de-
sign.

FIG. 6 is a top plan view of FIG. 5.

FIG. 7 is a front elevational view of FIG. 5.

FIG. 1

FIG. 2

FIG. 3

FIG. 5

FIG. 4

FIG. 6

FIG. 7
